US0D1072412S

(12) **United States Design Patent** (10) Patent No.: **US D1,072,412 S**
(45) Date of Patent: ** Apr. 22, 2025

(54) **TRASH CAN**

(71) Applicant: **simplehuman, LLC**, Torrance, CA (US)

(72) Inventors: **Frank Yang**, Rancho Palos Verdes, CA (US); **Myk Lum**, Irvine, CA (US); **Adam Wade**, Rancho Santa Margarita, CA (US); **Yoon Kim**, Long Beach, CA (US)

(73) Assignee: **simplehuman, LLC**, Torrance, CA (US)

(**) Term: **15 Years**

(21) Appl. No.: **29/871,943**

(22) Filed: **Mar. 2, 2023**

(51) **LOC (15) Cl. 09-09**

(52) **U.S. Cl.**

USPC **D34/9; D34/7**

(58) **Field of Classification Search**

(74) Attorney, Agent, or Firm — Knobbe, Martens, Olson & Bear, LLP

(57) **CLAIM**

The ornamental design for a trash can as shown and described.

DESCRIPTION

FIG. 1 is a top, front, right-side perspective view of a trash can showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures are for illustrative purposes and form no part of the claimed design.

1 Claim, 7 Drawing Sheets
